UNITED STATES PATENT OFFICE

166,087

DRESS

Tina Leser, New York, N. Y.

Application March 21, 1951, Serial No. 14,569

Term of patent 3½ years

(Cl. D3—26)

To all whom it may concern:

Be it known that I, Tina Leser, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my new design;

Fig. 2 is a front view of the dress shown in Fig. 1 with the shoulder points or flaps lowered and tied under the armpits.

Fig. 3 is a fragmentary rear view of the dress shown in Fig. 1.

I claim:

The ornamental design for a dress, substantially as shown and described.

TINA LESER.
